UNITED STATES PATENT OFFICE.

ALBERT GLOOR, OF CHICAGO, ILLINOIS, ASSIGNOR OF ONE-HALF TO
WILLIAM O. WAYMAN, OF CHICAGO, ILLINOIS.

DEVICE FOR APPLYING PASTE TO CORES.

No. 839,471.

Specification of Letters Patent.

Patented Dec. 25, 1906.

Application filed November 28, 1905. Serial No. 289,456.

To all whom it may concern:

Be it known that I, ALBERT GLOOR, a citizen of the United States, residing at Chicago, in the county of Cook and State of Illinois, 5 have invented a certain new and useful Device for Applying Paste to Cores, of which the following is a specification.

My invention comprises a device or mechanism for applying paste to the members of 10 sectional cores, which pasting has heretofore been done by hand; and the object of my invention is not only to provide a device or mechanism capable of doing the work heretofore done by hand, as just stated, but also 15 to provide a device or mechanism capable of better results than the hand method and of more rapid work.

The various features of advantage and 20 utility of my device will be apparent from the description hereinafter given.

In the drawings, Figure 1 is a plan view of my machine; Fig. 2, a side elevation thereof with a portion broken away to expose parts within the tank or receptacle which holds the 25 paste; Fig. 3, a section, partly in elevation, of a modified form of construction; and Fig. 4, a bottom plan view of the construction of Fig. 3.

Referring to the present embodiment of 30 my device or mechanism as herein shown, the same comprises a tank or receptacle 1, which may be varied as to size and dimensions, according to the size of the patterns to be operated upon or according to desire. 35 This tank, which may be made of any suitable material, is arranged to contain the paste usually employed for pasting sectional cores together.

My invention in its broadest aspect consists in providing a tank or receptacle as 40 above described and providing also means whereby the core and the surface of the paste may be brought into contact by either moving the core relatively to the surface of the 45 paste or so moving or raising the surface of the paste to contact the core. The first method described is illustrated in Figs. 1 and 2, the former method being the preferable one.

50 Referring to the construction of Figs. 1 and 2, I provide a supporting-plate 2 of such dimensions as to fit within the tank and to be suitably guided at the ends thereof, as by means of a series of vertical pins 3, which

form a bearing for the ends of this supporting-plate and keep the same from contact with the ends of the tank. This plate is arranged to receive and support the core, and in order that the same may move vertically in exactly a horizontal position I place or 60 mount this plate upon a frame which is capable of imparting or permitting to be imparted the desired movement to the supporting-plate 2, with the result that when the plate, with its core thereon, is depressed the 65 under side of the plate will contact the surface of the paste uniformly and evenly over the entire surface. This frame consists in the present instance of a series of rock-arms 70 4 and a pair of rock-shafts 5 near opposite ends of the tank, there being two rock-arms connected with each rock-shaft. Also in the present instance these rock-arms are so positioned as to support the four corners of the 75 plate and are, moreover, adapted to support the same and hold it elevated, as shown in Fig. 2, with a yielding pressure, as by means of counterweights hereinafter described. To provide for the necessary rolling action between the supporting-plate and the series 80 of rock-arms, these rock-arms are each made in the form of a yoke, as seen in Fig. 1, in whose outer ends is journaled a grooved roller 6, which is adapted to receive in such groove a depending guide 7, there being, of 85 course, in the present instance four of these rolling connections between the supporting-plate and its movable frame, as clearly indicated in Fig. 1. In order to compel all of the 90 rock-arms to move in unison, and thereby preserve the horizontal position of the supporting-plate at all elevations, I provide suitable connections between the rock-shafts 95 5, which in the present instance comprises two pairs of intermeshing quadrants 8, secured at the outer ends of the rock-shafts 5, which, as shown in Fig. 1, are projected through the sides of the tank. For the purpose of not only counterbalancing the supporting-frame, but also holding the same 100 in elevated position with a yielding pressure, I increase the weight of the quadrants at their outer end or provide the same with regular counterbalancing-weights 9, which may be of such increased weight as 105 to hold the supporting-plate in its upper position for the purposes already explained. In order to provide for the passage of the

paste through the plate when the latter is forced downwardly and to thereby apply the paste to the core, I provide the plate with a series of openings or slots which are of a character and of an arrangement which is varied according to the particular core being operated upon. In the present instance I have for the sake of a clear description of my invention illustrated a form of plate which is 5 adapted to the pasting of cores employed in the molding of cast-iron sections of boilers, such as the ordinary house-heating boiler, it being understood that the supporting-plate 2 is simply loosely or removably mounted 10 upon its supporting-frame and that such plate may be removed and another plate substituted according to the particular character of core to be operated upon. In the particular instance now being described the 15 plate is provided with a series of slots or openings 10, which are so formed or disposed as to give the greatest amount of opening permissible for the particular core to which this plate is adapted, so as to apply the paste 20 uniformly over the meeting surfaces of the core. By preference the plate is provided with strengthening-ribs 11, which also serve to support the portions 12 of the plate between the slots or openings. The plate is 25 also provided with an opening 13, through which additional paste may be supplied and which may be covered by a suitable lid or other closure, as may be desired. Furthermore, each plate may be provided with 30 guides 14, inclined inwardly and downwardly, so as to properly position the core upon the plate.

In practice the core is placed flat upon the supporting-plate with the side or surface to 35 be pasted resting upon such plate. The weight of the core of such weight increased by pressure of the hand causes the depression of the plate sufficient to bring the plate into contact with the surface of the paste, whereupon such paste is forced through the openings and upon the surface of the core. In 40 other words, the paste is stenciled upon the core. The core will now be found to be supplied with paste uniformly and evenly over 45 its surface, which is to be pasted onto its companion section, and the operation is repeated, with the result that the work is not only done with greater facility, but with better results as compared with the old and 50 well-known hand method of applying the paste. Instead of permitting the weight of the core or the pressure of the hand of the operator to depress the supporting-plate it is possible to operate the plate by simply 55 rocking the rock-shafts 5 by hand, either by manipulating the quadrants or providing an operating-handle upon one of the rock-shafts, which may be done in an obvious manner. Moreover, although I have described my invention as capable of applying paste to a 60

single core at one time it is obvious that the plate may be adapted to apply paste to a plurality of separate cores placed thereon in case such cores were of less size than the plate.

Referring next to the modified form of construction illustrated in Figs. 3 and 4, the supporting-plate 2 for the core instead of being made movable and thereby being brought into contact with the surface of the paste, is made 70 stationary and the reverse method adopted—that is to say, the paste is the movable element and is itself brought into contact with the supporting-plate. To accomplish this result, I provide the tank 1 with a supplementary chamber 1^a in the bottom thereof, which latter chamber is in the form of a piston-chamber to receive a piston 15. This piston is normally positioned at the bottom of the piston-chamber with the body of the 75 paste filling such chamber; but when such piston is elevated in the manner hereinafter explained the paste in such chamber is discharged into the tank proper, and the level of paste thereby raised in the latter. For 80 operating the piston the same is provided with a piston-rod 16, depending through the bottom of the piston-chamber in position to be contacted and operated by the crank-arm 85 17, secured to the rock-shaft 18, which shaft is adapted to be rocked by hand through the medium of the operating-handle 19, all as clearly indicated in Figs. 3 and 4.

In practice the core is laid upon the supporting-plate, which is here stationary, and the handle 19 is drawn to the left, Fig. 3, and the level of the paste thereby raised and the same brought into contact with the core through the openings in the plate.

I claim—

1. A device for pasting cores comprising, in combination with a tank or receptacle to contain the paste, mechanism for bringing the lower surface only of the core and the surface of the paste into contact to stencil 105 the paste onto the core.

2. A device for pasting cores comprising, in combination with a tank or receptacle to contain the paste, a support to receive the core, and means whereby the core and the 110 surface of the paste are brought into contact to stencil the paste onto the core.

3. A device for pasting cores comprising, in combination with a tank or receptacle to contain the paste, a perforated plate or support to receive the core and means for forcing the paste through the plate and stenciling it upon the core.

4. A device for pasting cores comprising, in combination with a tank or receptacle to 125 contain the paste, a plate to receive and support the core and having openings in accordance with the particular core to be pasted, and means for forcing the paste through said openings.

5. A device for pasting cores comprising, in combination with a tank or receptacle to contain the paste, a plate to receive and support the core and having openings in accordance with the particular core to be pasted, means for guiding the core in place on the plate, and means for forcing the paste through said openings.

6. A device for pasting cores comprising, 10 in combination with a tank or receptacle to contain the paste, a perforated plate to receive and support the core and arranged to be depressed upon the surface of the paste to force the latter through said perforations and 15 to stencil it upon the core.

7. A device for pasting cores comprising, in combination with a tank or receptacle to contain the paste, a horizontal plate to receive the core and having openings for the 20 passage of paste, and means whereby the plate is depressed upon the surface of the paste to force the latter through said openings and to stencil it upon the core.

8. A device for pasting cores comprising, 25 in combination with a tank or receptacle to contain the paste, a plate to receive the core and having openings in correspondence with the shape of the core for the passage for paste, and a compressible frame on which said plate is 30 supported.

9. A device for pasting cores comprising, in combination with a tank or receptacle to contain the paste, a plate to receive the core and having openings in correspondence with 35 the shape of the core for the passage of paste, and a compressible frame on which said plate is removably mounted.

10. A device for pasting cores comprising, in combination with a tank or receptacle to 40 contain the paste, and a perforated plate to receive the core and normally held above the surface of the paste with a yielding pressure, the perforations of said plate being in correspondence with the shape of the core.

11. A device for pasting cores comprising, in combination with a tank or receptacle to contain the paste, a plate to receive the core and having openings in correspondence with the shape of the core for the passage of paste, 45 and a compressible frame on which said plate is supported and normally upwardly pressed with a yielding pressure.

12. A device for pasting cores comprising, in combination with a tank or receptacle to 50 contain the paste, a perforated plate to receive the core, and a vertically-movable supporting-frame comprising a series of rock-arms supporting said plate at different points and movable in unison.

13. A device for pasting cores comprising, 55 in combination with a tank or receptacle to contain the paste, a perforated plate to receive the core, and a vertically-movable supporting-frame comprising a series of rock-arms having rollers at their ends to bear 60

against said plate, and means for causing said arms to rock in unison.

14. A device for pasting cores comprising, in combination with a tank or receptacle to contain the paste, a perforated plate to receive the core, and a vertically-movable supporting-frame comprising a series of rock-arms supporting said plate, means for operating said arms in unison, and means for counterbalancing the weight of the plate. 7c

15. A device for pasting cores comprising, in combination with a tank or receptacle to contain the paste, a perforated plate to receive the core, and a vertically-movable supporting-frame comprising a series of rock-arms supporting said plate, means for operating said arms in unison, and means for counterbalancing the weight of the plate and holding the same in an elevated position with a yielding pressure. 80

16. A device for pasting cores comprising, in combination with a tank or receptacle to contain the paste, a perforated plate to receive the core, and a vertically-movable supporting-frame comprising a series of rock-arms supporting said plate and intermeshing quadrant-arms connected with the rock-arms to compel uniform rocking of the rock-arms. 90

17. A device for pasting cores comprising, in combination with a tank or receptacle to contain the paste, a perforated plate to receive the core, and a vertically-movable supporting-frame comprising a series of rock-arms supporting said plate, and counterbalanced intermeshing quadrant-arms connected with the rock-arms to compel uniform rocking of the rock-arms. 95

18. A device for pasting cores comprising, in combination with a tank or receptacle to 105 contain the paste, a perforated plate to receive the core, and a vertically-movable supporting-frame comprising a pair of rock-shafts extending through the tank, rock-arms on said shafts, and intermeshing 110 quadrants secured to the ends of said rock-shafts to compel uniform rocking of the rock-arms.

19. A device for pasting cores comprising, in combination with a tank or receptacle to 115 contain the paste, a perforated plate to receive the core, and a vertically-movable supporting-frame comprising a series of rock-arms having grooved rolls at their free ends, and guides secured to the bottom of the 120 plate and bearing in the grooves of the rolls.

20. A device for pasting cores comprising, in combination with a tank or receptacle to contain the paste, a vertically-movable perforated plate to receive the core, and guide-pins at the sides of the tank to guide the edges of the plate. 125

21. A device for pasting cores comprising, in combination with a tank or receptacle to contain the paste a counterbalanced perfo- 130

rated plate adapted to receive the core and, when depressed, adapted to bring the core and surface of the paste into contact, said plate being perforated in accordance with the 5 particular core so as to stencil the paste upon the pasting portions thereof.

22. A device for pasting cores comprising, in combination with a tank or receptacle to contain the paste, a plate adapted to receive 10 the core and having openings for the passage of the paste, and means for counterbalancing

the weight of the plate, but permitting the weight of the core to depress such plate and thereby bring the core and the paste into contact, said plate being perforated in accordance with the particular core so as to stencil 15 the paste upon the pasting portions thereof.

ALBERT GLOOR.
